UNITED STATES PATENT OFFICE.

JAMES E. WALLACE AND CHARLES D. REESE, OF LA CROSSE, WISCONSIN.

EXTENSION-TRESTLE.

SPECIFICATION forming part of Letters Patent No. 380,539, dated April 3, 1888.

Application filed July 21, 1887. Serial No. 241,956. (No model.)

To all whom it may concern:

Be it known that we, JAMES E. WALLACE and CHARLES D. REESE, of La Crosse, Wisconsin, have invented certain Improvements in Extension-Trestles, of which the following is a specification.

Our invention relates to an improvement in extension-trestles, designed especially for use by carpenters, masons, and other artisans; and the object of our invention is to provide a trestle which is adapted to be vertically and longitudinally adjusted, and which may be readily taken apart and erected.

To these ends the invention consists in the peculiar construction and combination of devices that will be hereinafter more fully set forth.

The accompanying drawing is a perspective view of our improved trestle.
20 A, B, and C represent a series of bars which overlap each other, the bars A C being arranged on one side of the bar B. Near one end of the bar B are secured a pair of rectangular metallic guides or straps, D, which embrace the bar 25 A, and near one end of the bar C are secured a pair of similar straps or guides, D', which embrace the bar B. By this means the bars A C are secured firmly to the bar B, and are at the same time adapted to be moved longitudinally 30 on said bar toward or from each other to adjust the trestle to any length required.

G represents three pairs of downwardly-diverging legs, which are attached to the center and opposite ends of the bars B A C, respectively. Each pair of legs G is connected by a cross-bar, G', and braces G² connect the said cross-bars to the extensible bars. The lower 35 end of each leg G is provided with a pair of

rectangular straps or keepers, H, which are similar to the keepers or straps D D'. 40

E represents extensions, which are arranged on the outer sides of the legs G and are guided by the straps or keepers H. To the outer side of each extension is secured a rack-bar, E', having a series of notches, as shown. Each of the 45 legs G has a set-screw, I, the point of which is adapted to engage the proximate bar E', so as to force the same outward and cause the keepers or straps to engage the notches in the rack-bar, and thereby secure the extension at any 50 desired adjustment to the leg.

From the foregoing description it will be readily understood that the trestle may be adjusted longitudinally and vertically, and thereby adapted for use in a great variety of 55 circumstances.

Having thus described our invention, we claim—

The combination, in a trestle, of the supporting-legs G, having the straps H rigidly secured thereto, the extensions E, having the racks E' on the outer sides, said extensions being passed through the straps H and movable longitudinally on the legs G, and adapted to play loosely between the opposing sides of said legs and said straps, and the set-screws engaging threaded openings in legs G, and having their points bearing against the inner sides of the extensions, for the purpose set forth, substantially as described. 60 65

JAMES E. WALLACE.
